UNITED STATES PATENT OFFICE

WILLIAM F. DETWILER, OF TARENTUM, PENNSYLVANIA

FURNACE

Application filed March 9, 1929. Serial No. 345,818.

This invention relates to furnaces and more particularly to so called continuous furnaces for use in annealing or otherwise treating iron, steel or alloy sheets or other objects.

An object of this invention is to provide a furnace of the type set forth of an improved construction and arrangement.

As heretofore constructed furnaces of this type have been provided with various forms of conveyor mechanisms, none of which have been satisfactory for various reasons, among others, the fact that they were not protected in any way from the heat of the furnace and hence deteriorated rapidly or, second, they opened the interior of the heated chamber to the atmosphere.

A further object of this invention is to provide a furnace having a conveyor mechanism free of these and other defects.

A further object is to provide a furnace of the type set forth constructed and arranged to mechanically unload material from the conveyor after it has passed through the furnace.

These and other objects which will be apparent to those skilled in this particular art are accomplished by means of the invention illustrated in the accompanying drawings in which Fig. 1 is a transverse sectional view through the furnace and conveyor mechanism constructed in accordance with one embodiment of this invention. Fig. 2 is a view in side elevation of the delivery end of applicant's conveyor mechanism at the unloading zone. Fig. 3 is a similar view of the loading end. Fig. 4 is a perspective view of certain details of construction and Fig. 5 is a plan view of one form of unloader.

Although the particular form of the present invention which has been chosen for the purposes of illustration is shown in the form of an annealing furnace for annealing sheets, it will be apparent that the invention is equally applicable to other types of furnaces employed in connection with other forms of work.

As illustrated, the furnace 10 has the usual heating chamber 11 heated by means of suitable burners 12 of any desired type ex-

tending through the walls 13. The roof is formed by separate blocks 14 positioned so as to provide a slot 15 extending therethrough throughout the entire length of the furnace and the inner edge of each roof-forming block engages and is supported by suitable block supporting shoulders 16 formed on opposite sides of a hollow casting 17 extending throughout the length of the furnace roof and supported from overhead cross beams 18 mounted on vertically extending side members or supports 19 spaced at suitable intervals along the outside wall of the furnace.

The roof supporting casting is composed of a plurality of sections identical in form and bolted together to form in effect a single continuous structure. Each section is so shaped as to provide a conveyor chamber 20 having a slot 21 extending from the bottom of the chamber to the slot 15 in the furnace roof and forming, in effect, an extension thereof, with the result that the conveyor chamber 20 and the heating chamber 11 of the furnace are connected by a continuous slot, the interior of the furnace is thereby sealed around the conveyor. The casting also is formed to provide a water chamber or cooling trough 22 or the like disposed around the conveyor chamber 20 and on opposite sides of the slot 21, through which cooling water is circulated for the purpose of protecting the conveyor mechanism and associated parts from the furnace heat.

As illustrated in Fig. 4, the conveyor chamber 20 in each casting section 17 is open at the ends so that the total length of such chamber depends upon the number of sections placed end to end. The cooling chambers or water troughs 22 are closed at each end of each section and cooling fluid is delivered to the bottom of each chamber 22, on each side of the wall of the slot 21 by inlet pipes 23 connected by a suitable connecting pipe 24 with a cold water supply line 25 which may conveniently be mounted on the cross member 18. Used water is withdrawn from the top of each chamber 22 by an outlet pipe 26 communicating with a discharge line 27.

One run of an endless conveyor 28 having spaced article supporting hooks 29 loosely pivoted in the ends of the supporting members 30 is arranged to extend and move through the conveyor chamber 20, passing around a driving sprocket 31 at the delivery end of the furnace and around an idler sprocket 32 at the unloading end. These movably supported hooks are positioned or disposed to suspend sheets longitudinally from the conveyor. The driving sprocket is operated from any suitable source of power such as an electric motor 33 through any standard reduction drive and is spaced from the end of the associated furnace a sufficient distance to provide a zone in which an operator may load the conveyor with sheets 34 to be annealed or otherwise treated. The idler sprocket 32 which is yieldingly drawn outwardly by a weighted lever 35 is also spaced from the delivery end of the furnace a sufficient distance to provide a zone for unloading the sheets as they emerge from the furnace. Conveyor supporting troughs 36 are bolted to each end section 17 of the castings and provide supports for the conveyor runs through the loading and unloading zones at each end of the furnace, and the return run of the conveyor passes over supports 37 above the cross beams 18.

Each sheet 34 is provided with perforations 38 near the upper edge so that each hook of a pair of same can be hung from the sheet supporting hooks 29 of the conveyor and pass through the furnace in a suspended state. As they emerge from the furnace each hook of the pair encounters an unloader 39 in the form of an angular or curved rail which engages the face of each hook of a pair of hooks and pushes it out of engagement with the associated sheet as shown in Fig. 6 and swings them to a position where the associated sheet is released and taken by the operator.

The conveyor chamber 20 is so formed and positioned with relation to the associated cooling chamber that a relatively large quantity of cooling fluid is continually circulating through the space between the conveyor chamber and the heating chamber so as to effectively protect the former from the heat of the latter. At the same time, the direct communication through the slot between the heating chamber and the conveyor chamber does not permit the escape of heat therethrough as the chamber itself is so formed as to provide a seal. The cooling chamber is so formed as to constitute a part of the roof supporting structure providing a single effective apparatus.

Although I have described a specific form of furnace and conveying mechanism in more or less detail, it will be apparent that various changes, additions, substitutions and omissions may be made therein without depart-

ing from the spirit of this invention or the scope of the appended claims.

What I claim as new and desire to secure by Letters Patent is:

1. A heating furnace including a roof and having in combination a conveyor associated with said roof for continuously moving material through the furnace and a water cooled conveyor chamber disposed around the upper portion of said conveyor and provided with roof supporting members formed thereon. 70
2. A heating furnace having in combination a conveyor for continuously moving material therethrough and a casting associated with said conveyor and formed so as to provide a conveyor chamber in which the upper portion of said conveyor is located and a supporting chamber for cooling fluid and means for circulating a cooling fluid through said supporting chamber. 80
3. A heating furnace having in combination a conveyor for continuously moving material through said furnace and a series of similar castings cooperating to form a conveyor chamber through which said conveyor moves and to form a cooling chamber therefor, and means for passing a cooling fluid through each of said castings. 85
4. A heating furnace having in combination a slotted roof, a conveyor chamber having a slotted wall cooperating with the slot in said roof, a conveyor located in said chamber and having material supporting arms extending through said slots for continuously moving material through said furnace and means for circulating a cooling fluid around said conveyor chamber past and in contact with the walls of said conveyor chamber and of said slot. 95
5. A furnace having in combination a slotted roof, a roof supporting frame formed so as to provide a closed top conveyor chamber communicating with said slot and a cooling chamber disposed around the outside of said conveyor chamber and said slot and means for circulating a cooling fluid through said cooling chamber. 105
6. A furnace having a roof, a frame having roof supporting flanges formed thereon and so shaped as to provide a conveyor chamber and a water compartment disposed around said conveyor chamber and means for circulating water through said compartment. 115
7. The combination with a furnace of a roof, a sectional frame associated with said roof and provided with roof supporting flanges, each section of said frame having an open ended conveyor chamber formed therein and a compartment disposed around the outside of said chamber, means for supporting said sections in abutting relationship to form a conveyor chamber throughout the length of the furnace roof and means for cir- 120
- 65 125
- 66 130

culating cooling water through each of said compartments.

8. A heating furnace having in combination a conveyor for continuously moving material therethrough, a chamber disposed around the upper portion of said conveyor, a water chamber disposed around said conveyor chamber, means for conducting cooling water to the bottom of said water chamber and means for discharging the partially warmed water from the top of said water chamber.

9. A heating furnace having in combination a conveyor associated therewith for continuously moving material therethrough, a roof supporting member having a conveyor chamber, said conveyor chamber having a water chamber, disposed therearound for cooling the latter.

10. A heating furnace including a roof and having in combination a conveyor associated with said roof for continuously moving material through the furnace, a water chamber for cooling said conveyor having means for supporting the roof of said furnace.

11. A heating furnace including a roof and having in combination a conveyor associated with said roof for continuously moving material through the furnace, a member supporting said roof which includes a chamber disposed around the upper portion of said conveyor, and a water chamber disposed around said first mentioned chamber for cooling it.

12. A heating furnace including a roof and having in combination a conveyor associated therewith for continuously moving material through the furnace, a unitary member including a chamber disposed around said conveyor and a water chamber disposed around said first mentioned chamber, said water chamber having projecting shoulders for cooperating with slots cut in the roof, so that said roof will be supported by said member.

13. A furnace having in combination a conveyor for continuously moving material therethrough, means including a plurality of movably supported hooks positioned for suspending sheets longitudinally from said conveyor, and an unloading rail positioned longitudinally of said conveyor simultaneously engaging each hook of a pair suspending a given sheet, for pushing said hooks out of engagement with the sheet suspended therefrom.

14. A furnace having a roof, a channel-shaped roof supporting frame having a centrally disposed conveyor chamber for the furnace, the space between said chamber and the sides of said frame providing a water compartment for cooling the chamber.

15. A furnace having a roof, a channel-shaped roof supporting frame having a centrally disposed conveyor chamber for the

furnace, the space between said chamber and the sides of said frame providing a water compartment for the cooling chamber, said water chamber having projecting shoulders for cooperating with slots cut in the roof, so that said roof will be supported by said member.

In testimony whereof, I have hereunto subscribed my name this 5th day of March, 1929.
